CATALYTIC IGNITER FOR GASEOUS FUELS

Robert S. Taylor, Evansville, Ind., assignor to
Servel, Inc., New York, N. Y., a corporation of
Delaware

Application April 12, 1944, Serial No. 530,673

9 Claims. (Cl. 158—115)

1

My invention relates to ignition devices and more particularly to automatic catalytic lighters for domestic gas ranges.

Catalytic igniters have been used heretofore for igniting illuminating gas. However, due to the fact that the various gases used contain impurities which tend to poison the catalyst, these igniters have not proven entirely satisfactory.

It is therefore an object of my invention to provide a catalytic igniter wherein fuel gas is ignited without poisoning the catalyst.

It is a particular object of my invention to provide an automatic igniter for gas ranges wherein a pure fluid such as one of the alcohols is used as an auxiliary fuel.

It is another particular object of my invention to provide an automatic igniter for gas ranges wherein the opening of any one gas cock simultaneously operates said igniter without interfering with the setting of the other gas cocks, and wherein the opened gas cock will be automatically returned to its closed position in the event that that particular gas cock has not been initially opened beyond a predetermined point.

These and other objects of my invention will be apparent from the following description taken with the accompanying drawings which form a part of this specification, and wherein:

Fig. 1 is a partial top plan view of a gas range, partly in section, illustrating one embodiment of my invention;

Fig. 2 is an elevational view, partly in section, taken substantially on line 2—2 of Fig. 1;

Fig. 3 is a vertical sectional view on line 3—3 of Fig. 1;

Fig. 4 is a detail showing of a cam and bellows arrangement when the gas cock is in closed position;

Fig. 5 is a view similar to Fig. 4 but with the gas cock fully open;

Fig. 6 is a broken top plan view of a gas range illustrating a second embodiment of my invention;

Fig. 7 is a vertical sectional view on line 7—7 of Fig. 6;

Fig. 8 is a top plan view, partly in section, of a bellows operating mechanism;

Fig. 9 is a vertical sectional view on line 9—9 of Fig. 7;

Fig. 10 is a vertical sectional view on line 10—10 of Fig. 6; and

Fig. 11 is a vertical sectional view on line 11—11 of Fig. 6.

Referring now to Figs. 1—5 inclusive wherein one embodiment of my invention is illustrated

2

and wherein like reference characters are used to designate like parts, the numeral 20 designates a gas range having a conventional burner 21 and gas cock 22. A bellows 23 is mounted along side the gas cock and is operated by a cam 24 mounted on the gas cock. An air conduit 25 leads from the bellows and is connected to an auxiliary fuel container 26. Container 26 is provided with a removable cap 27 by which the container may be filled with an alcohol or other highly volatile and combustible auxiliary fuel which does not have any detrimental effect on the catalyst. Container 26 is partly filled with a loose fibrous material 28 which is held in place by a wire screen 29. A conduit 30, of relatively small cross-section, leads from container 26 and is connected to a spherical igniter 31. The igniter is filled with a granular catalytic material 32 which may be platinum black or any other suitable catalytic material. The catalyst is held in place by means of wire screens 33, the mesh of which is close enough to hold the catalytic material in place and still loose enough to permit gas and the flame thereof to pass through said screen. A flash tube 34 leads from gas burner 21 and is removably connected to igniter 31 by means of removable clips 35; the arrangement is such that an air space 36 is provided between said tube and said igniter. Check valves 37 and 37' are provided in the bellows 23 and in the connection 38 between conduit 30 and igniter 31, respectively.

The operation of this igniter is as follows, when gas cock 22 is opened fuel gas flows to burner 21 and simultaneous with the opening of the gas cock, cam 24 compresses bellows 23 forcing air through conduit 25 into container 26 and through conduit 30 into igniter 31. This air in passing through container 26 picks up alcohol vapor therefrom and carries said vapor to the catalytic material 32 where it is oxidized by the air in the presence of the catalyst. The oxidation of the alcohol vapor generates a high temperature in the catalyst which ignites the vapor, which in turn ignites fuel gas which passes from the burner 21 through flash tube 34 and the flame is carried back through said tube to ignite the gas at the burner. The amount of alcohol vapor that is forced over the catalytic material each time the gas cock is opened is exceedingly small; therefore, the necessity for refilling the container with alcohol would be very infrequent.

Referring now to Figs. 6 to 11 inclusive, wherein a second embodiment of my invention is illustrated, the numeral 40 designates a gas range

equipped with conventional burners 41. Each burner is provided with a jet 41' which directs fuel gas into flash tubes 42 leading from the burners to a central igniter 43. This igniter consists of a housing 44 provided with a removable cover 45 which is provided with openings 46. The bottom of the housing is provided with openings 47. A catalytic igniter 48 consisting of a plurality of strands of platinum or platinum-rhodium wire is mounted on an annulus 49 which is screw-threaded onto a vapor conduit 50. The arrangement is such that by removing the cover 45 the igniter is accessible and may be removed for inspection or repair. A conduit 51, of relatively small cross-section, leads from an auxiliary fuel container 52 and is connected by means of a sleeve 53 to vapor conduit 50. The sleeve 53 is provided with a check valve 54.

This range 40 is provided with a conventional gas manifold 55, gas conduits 55' and gas cocks 56. A U-shaped channel member 57 is mounted under the gas cocks and is welded to or otherwise fixedly secured to supports 58. A plurality of bolts or sliding members 59, one for each gas cock, fit snugly within channel 57 and are guided for limited reciprocal movement therein by means of a pivot pin 60 which travels in guides 61 in each side of the channel. A trigger 62 is pivotally mounted on pivot pin 60 within each bolt 59. Each of these triggers is provided on its upper surface with a flat horizontal portion 63 and an inclined or cam portion 64; the horizontal portion is substantially flush with the top of the bolt. A spring 65 is mounted in an opening in the trigger and tends to rotate the trigger in a counter-clockwise direction. A detent 66 is provided at one end of each trigger and fits under a ledge 67 on the bolt to limit counter-clockwise rotation of the trigger. A latch 68 projects downward from the opposite end of the trigger and engages the end 69 of a slot 70 in plunger 71. This plunger 71, which is provided with a plurality of slots 70, one under each trigger, is mounted for sliding movement under the channel 57 and is provided at one end with a dash pot 72 which is fixedly mounted on the channel. A spring 73 encircles the rounded portion 74 of plunger 71 with one end thereof bearing against one head of the dash pot and the other end bearing against a piston 75 which is attached to the rod 74. By this means the plunger 71 is biased toward the position shown in Fig. 7. The opposite end of plunger 71 contacts a bellows 76 which is connected by a conduit 77 to the auxiliary fuel container 52. This bellows is provided with a spring pressed check valve (not shown) similar to the check valve 37 of Fig. 5. An arm 78 is rigidly attached to the lower portion of each of the gas cocks 56 and is adapted to be rotated with the gas cock to slide an adjacent bolt 59 to the left as viewed in Fig. 6.

The operation of the igniter illustrated in Figs. 6 to 11 inclusive is as follows, when any one of the gas cocks 56 is opened to admit fuel gas to its particular burner the arm 78 of that gas cock contacts the adjacent trigger 62 sliding it and its attached bolt 59 to the left as viewed in Fig. 6 with the result that latch 68 pushes the plunger 71 to the left compressing the bellows 76 forcing air through conduit 77, auxiliary fuel container 52, conduits 51 and 50 into the igniter. This air in passing through the container 52 picks up alcohol vapor and carries said vapor to the platinum wires of the igniter where the vapor is oxidized by the air in the presence of the platinum wires. As stated above, the oxidation of this va-

por generates a high temperature in platinum wires causing them to glow and ignite the fuel gas which passes from burner jet 41' through flash tube 42. The flame then passes back through the flash tube and ignites the fuel gas at that particular burner.

The arms 78 and triggers 62 are so proportional and arranged that when a gas cock has been turned through approximately 45°, in other words, about one-half open, the arm slides past the end of the trigger and the dash pot 72 operates to return the plunger 71 to its original position. The plunger in returning to its original position carries the trigger 62 and attached bolt 59 to their original positions. Travel of each of the bolts 59 is limited by pivot pins 60 which travel in guide ways 61 on each side of the channel 57.

After a gas cock has been turned through 45° and the plunger and bolt have been returned to their original positions the gas cock may be adjusted to any desired setting without being interfered with by the adjacent bolt and trigger. In other words, the arm 78 may be freely moved back and forth above the trigger and when the gas cock is turned to the off position arm 78 rides over the top of the inclined portion 64 of the trigger depressing it into the slotted portion of the bolt. In order to insure ignition of the fuel gas each time a gas cock is opened, the gas cock must be turned through at least 45°, otherwise the dash pot in returning the plunger to its inactive position will return the gas cock to its closed position. If, on the other hand, the gas cock has been turned through or beyond 45°, the bellows will supply adequate air and alcohol vapor to the igniter to ignite the fuel gas, and since the operating arm has slipped past the trigger the return of the plunger, bolt and trigger has no effect on the open gas cock. Also it is to be noted that with the arrangement illustrated in Figs. 6 to 11 inclusive the opening of any gas cock will automatically ignite the fuel gas at that burner, and that the opening of any one gas cock has no effect upon the setting of any other of the gas cocks. This is true because of the slots 70 in the plunger and of the independent movement of the bolts 59 relative to each other.

While I have illustrated and described but two specific embodiments of my invention it is obvious that the invention may take many other forms. Also, while the invention has been illustrated in connection with the top burners of a gas range, it obviously may be used with equal facility with the oven and broiler burners, or, as a matter of fact, with any gas burner. It is therefore to be understood that my invention is limited only by the following claims.

I claim:

1. An ignition device for fuel gas comprising a gas burner, a gas cock for supplying gas to said burner, a reservoir for an auxiliary fuel, means for delivering air to said reservoir, a catalytic igniter, and mechanism operated by movement of said gas cock for operating said air supply means for delivering air and entrained auxiliary fuel from said reservoir to said catalytic igniter to ignite the fuel gas supplied to said burner.
2. An igniter for fuel gas comprising a gas burner, a gas cock for supplying fuel gas to said burner, a reservoir for auxiliary fuel, a catalytic igniter, a bellows for supplying air to said reservoir, a conduit leading from said reservoir to said igniter, and mechanism connected to said gas

cock for operating said bellows simultaneously with the opening of said gas cock.

3. An igniter for fuel gas comprising a gas burner, a gas cock for regulating the supply of fuel gas to said burner, a reservoir for an auxiliary fuel, a catalytic igniter, a conduit connecting said reservoir to said igniter, an air pump connected to said reservoir, and mechanism operated by movement of said gas cock for operating said air pump.

4. An automatic gas igniter comprising a gas burner, a valve for controlling the supply of gas to said burner, a catalytic igniter, a reservoir for an auxiliary combustible fluid, a conduit connecting said reservoir to said igniter, mechanism operated by movement of said valve for supplying auxiliary combustible fluid from said reservoir to said catalytic igniter simultaneous with the supply of gas to said burner, and means for directing gas from said burner to said igniter.

5. An igniter for domestic gas ranges comprising a plurality of gas burners, a gas supply valve for each of said burners, a common catalytic igniter for said burners, flash tubes leading from said burners to said catalytic igniter, a reservoir for an auxiliary combustible fluid, a conduit connecting said reservoir to said catalytic igniter, and mechanism operatively connected to each of said valves for supplying auxiliary combustible fluid from said reservoir to said igniter.

6. An igniter for domestic gas ranges comprising a plurality of gas burners, a gas supply valve for each of said burners, a common catalytic igniter for said plurality of burners, means for directing gas to said igniter, a reservoir for an auxiliary fluid, a conduit connecting said reservoir with said igniter, an air pump connected to said reservoir to supply air and entrained combustible fluid to said catalytic igniter.

7. An igniter for gas ranges comprising a plurality of burners, a gas supply valve for each of said burners, a catalytic igniter, means for supplying gas to said catalytic igniter, a reservoir for an auxiliary combustible fluid, a conduit connecting said reservoir to said catalytic igniter, an air pump connected to said reservoir, and mechanism operatively connected to each of said gas supply valves for independently operating said air pump for supplying air and entrained combustible fluid to said catalytic igniter.

8. An igniter for gas ranges comprising a plurality of burners, a gas supply and regulating valve for each of said burners, a catalytic igniter, means for directing gas from each of said burners to said catalytic igniter, a reservoir containing an auxiliary combustible fluid, a conduit connecting said reservoir to said catalytic igniter, an air pump connected to said reservoir, mechanism operatively connected to and operated by each of said valves for operating said air pump upon opening of any one of the gas valves, and structure operatively connected to said mechanism for returning said one gas valve to its closed position in the event that said one valve is not initially opened beyond a predetermined point.

9. A gas range comprising a plurality of gas burners, a gas valve for each of said burners, a catalytic igniter, flash tubes located between said burners and said igniter, a reservoir containing a combustible fluid, a conduit leading from said reservoir to said igniter, an air pump connected to said reservoir, and mechanism operatively connected to each of said valves for actuating said air pump simultaneous with the opening of any one of said valves, whereby air and entrained combustible vapor is supplied to said igniter.

ROBERT S. TAYLOR.
